Henry W. Williams

UNITED STATES PATENT OFFICE.

DAVID W. LOW, OF GLOUCESTER, MASSACHUSETTS.

LIFE-SAVING APPARATUS FOR BOATS.

SPECIFICATION forming part of Letters Patent No. 280,842, dated July 10, 1883.

Application filed March 19, 1883. (No model.)

To all whom it may concern:

Be it known that I, DAVID W. Low, of Gloucester, in the county of Essex and State of Massachusetts, have invented new and useful 5 Improvements in Life-Saving Apparatus for Boats, of which the following is a specification.

This apparatus is especially applicable to dories, but it may be used in connection with boats of any style or build; and the invention 10 consists in a dory or other boat constructed as below described, in order that it may include in its construction apparatus for saving and sustaining life.

In the accompanying drawings, in which 15 similar letters of reference indicate like parts, Figure 1 is a cross-section of a dory constructed so as to embody my improvements. Fig. 2 is a plan of the compartment or box with the cover laid back. Fig. 3 is an enlarged plan 20 of the underside of the boat at the point of one of the plugs. Fig. 4 is an enlarged vertical section of the bottom of the boat at the same point.

A represents the bottom, and A' the sides, 25 of a dory.

a is the rail, and B the rowing-thwart.

C is a box or compartment, of which C' is 30 the cover or lid, provided with chambers D, containing bottles or packages of food in liquid or other form, E, and chambers F G by the side of the chamber D, containing, respectively, the upper and lower "life-lines," f g. When not in use these life-lines lie in their chambers with the knots or rings f' g' in the 35 chambers h in the plugs H, suitable passages being prepared leading from the chambers F G to the chambers h.

I is the cover of the plug H, hinged at J thereto, and having its rear end, I', of the shape 40 shown, whereby it bears against the spring K, and is held shut or open in a vertical position by the pressure of said spring, which may be of rubber or other material. A space, L, is left, so that the fingers may be inserted and the 45 cover operated. An elastic ring or packing, P, prevents ingress or egress of water.

R R are vessels to be used for bailing purposes, provided with the handles R' (secured to the rails a by the lanyards T) and the beackets or straps S.

The operation of the apparatus is as follows:

In case the dory is capsized the men grasp, by means of the spaces L, the lids I of the plugs H, swing open said lids, and grasp the knotted ends g' f' of the life-lines g f, which are prevented from entirely leaving the plugs by knots in their opposite ends. These life-lines are used to right the boat. Then by coiling the lines about their bodies the men have their hands free and can grasp the bailing-vessels 60 (having first hauled them up by means of the lanyards T) by the handles R' and beackets S and bail out the boat. Then by lifting the cover C the food in the chambers D is reached, by means of which life may be sustained for a 65 considerable time.

The plugs may be so placed as to allow the life-lines to pass through the bottom or the sides of the boat, as desired.

Although the shape shown of the bailing-vessel R is perhaps preferable, I do not confine myself to it.

The box C is of course properly secured to the bottom of the boat, and may be centrally or otherwise situated therein, or it may be secured to any other portion of the boat if found practicable.

Having thus fully described my invention, what I claim, and desire to secure by Letters Patent, is—

1. The combination, with the bottom A of a boat, of the metallic plug H, provided with the lid I I', spring K, and packing P, substantially as and for the purpose set forth.

2. The combination, with the bottom A of a boat, of the metallic plug H, provided with the lid I and chamber h for the reception of the end or handle of a life-line, substantially as and for the purpose described.

3. The combination of a life-line placed in the inside of a boat and passing through its bottom or side, and a boat so constructed that said life-line may be reached from the outside of the boat and drawn through the bottom or sides of the same, substantially as and for the purpose set forth.

4. In a boat, the combination therewith of the box C, placed in the bottom thereof and provided with the lid C', said box being also provided with the longitudinally arranged food-chambers D D, made end to end, and the longitudinal life-line chambers F G, arranged

side of said food-chambers and one above the other, substantially as and for the purpose described.

5. In a boat, the combination of the box C, conveniently placed therein, and provided with chambers or compartments F G for the reception of life-lines, the life-lines f g and the plugs H, set into the boat and connecting with said chambers, said plugs being separated from 10 the outside of the boat by lids I, and provided with chambers h for the reception of the knotted or enlarged ends f' g' of the life-lines, whereby separation of the lines from the boat

is prevented, substantially as and for the purpose set forth.

6. In a boat, the combination therewith of the bailing-vessels R, placed against the sides thereof, and secured to the rail by means of lanyards T, extending from said rail to handles R' of the vessels, said vessels being also 20 provided with beackets S, substantially as and for the purpose described.

DAVID W. LOW.
